[57] **CLAIM**

The ornamental design for a combined pickup cab carrier and roll bar, as shown and described.

DESCRIPTION

FIG. 1 is a perspective view of a combined pickup cab carrier and roll bar showing my new design, it being understood that the broken lines are for illustrative purposes only;

FIG. 2 is an enlarged side elevational view thereof, the opposite side being substantially a mirror image of the side shown therein;

FIG. 3 is an enlarged rear elevational view thereof; and FIG. 4 is an enlarged front elevational view thereof. The broken lines in FIG. 1 of the drawing are for illustrative purposes only.

FIG. 2

FIG. 1

FIG. 3

FIG. 4
